BROACHING MACHINE

William D. Averill, Cincinnati, Ohio, assignor to
The Cincinnati Milling Machine Company, Cincinnati, Ohio, a corporation of Ohio

Application March 21, 1938, Serial No. 197,044

18 Claims. (Cl. 90—33)

This invention relates to machine tools and more particularly to broaching machines.

One of the objects of this invention is to provide an improved cycle of operation for a single ram broaching machine.

Another object of this invention is to provide a single ram broaching machine with improved means for simultaneously broaching a plurality of work pieces.

10 A further object of this invention is to provide a broaching machine with automatic means for unclamping and unloading a work piece.

15 An additional object of this invention is to provide an improved automatic cycle control mechanism having sequential interlocks for insuring that each step in the cycle is completed before the next movement begins.

20 Other objects and advantages of the present invention should be readily apparent by reference to the following specification considered in conjunction with the accompanying drawings illustrative of one embodiment thereof, but it will be understood that any modifications may be made in the specific structural details within the scope 25 of the appended claims without departing from or exceeding the spirit of the invention.

Referring to the drawings in which like reference numerals indicate like or similar parts:

20 Figure 1 is a side elevation of a portion of a broaching machine embodying the principles of this invention.

Figure 2 is a plan view partly in section of the machine shown in Figure 1, and as viewed on the line 2—2 of that figure.

35 Figure 3 is a detail vertical section through one of the work holders and showing the automatic ejector.

Figure 4 is a detail section of a portion of the control mechanism as viewed on the line 4—4 of Figure 1.

40 Figure 5 is a detail section on the line 5—5 of Figure 3.

Figure 6 is an enlarged plan view of the work holding mechanism.

45 Figure 7 is a detail section on the line 7—7 of Figure 6.

Figure 8 is a diagram of the hydraulic control circuit.

Referring to Figures 1, 2, and 3 of the drawings, the reference numeral 10 indicates the vertical column of a broaching machine, and this column is provided with V-guideways 11 and 12 for receiving a vertically reciprocable ram 13. The front of the ram is provided with a dovetailed 55 guide 14 in which is adjustably mounted and

clamped a broach holder 15, the broach holder having two sets of broaching teeth 16 and 17 parallelly mounted thereon for simultaneous operation on separate work pieces. The broaching tools may be secured to the holder 15 by 5 clamping screws 18 threaded into the back of the tools, as more particularly shown in Figure 3.

The column 10 is provided with an integral knee 19 for supporting a work table 20. A work fixture 21 is secured to this table. The fixture is 10 provided with two upstanding mandrels 22 and 23, and each mandrel, as shown in Figure 3, has a reduced portion 24 which fits in a bore in the work fixture. The shoulder 25 of the mandrel rests on a wearing ring 26, the ring also supporting the work. Each mandrel has a rectangular slot 27 cut in the upper portion thereof in which is mounted a work clamping member 28. This member is supported on a pair of pins 29 which pass through elongated holes 30 whereby the 20 member is free to move laterally a limited amount.

The work clamping member 28 has an arcuate slot 31 cut in one side for receiving a roller 32 which is rotatably supported on a pin 33. A clamp actuating rod 34 passes through the mandrel and has a wedge shaped head 35 which is adapted to engage the roller 32 for moving the clamping member radially into engagement with a work piece. These work fixtures are particularly adaptable for holding cylindrical work pieces, such as the piece 36, and these pieces are formed by rolling flat stock into cylindrical form and then welding the abutting ends. The broaching operation performed on these pieces consists in broaching or cutting off the excess 35 metal at the welded seam, as indicated by the reference numeral 37 in Figure 2.

A three point clamp is provided for each work piece comprising two angularly spaced abutments 38 and 39 which are fixed to the work fixture by 40 clamping screws 40, as more particularly shown in Figure 7. These pieces have arcuate surfaces against which the exterior surface of the work is forced by the clamping member 28 which engages the inside surface of the work. When the 45 clamping member 28 is released, a pair of spring pressed plungers 41 located in each abutment serves to move the work piece away from the abutments a predetermined amount thereby assisting in retracting the clamping member 28 for 50 insertion of the next work piece.

The operator loads the fixtures by hand, and then the rods 34 are moved downward by power means to clamp the work, the member 28 moving forward to thereby move the work forward 55

into engagement with the two fixed abutments carried by the fixture whereby the work is held by a three point support.

The rods 34 are actuated by power cylinders 42 which, as shown in Figure 1, are pivotally supported at 43 on the under side of table 20. Each cylinder has a piston 44 which is connected by a piston rod 45 to a centrally pivoted lever 46 which has its other end connected with the rod 34. 5 The cylinders are connected in parallel to a control valve 47. In other words, a channel 48 is connected to ports 49 and 50 located in the lower end of the respective cylinders, and a channel 51 is connected to ports 52 and 53 located in the upper end of the respective cylinders. The valve 47 has a pressure port 54 which is supplied with pressure fluid, such as compressed air, from a suitable source indicated by the reference numeral 55. Thus, when the port 54 is connected to channel 48, the pistons 44 move up to clamp the work; and when connected to the channel 51, the pistons move down to release the work. The valve 47 is a rotary valve having an operating handle 56, which is connected by a link 57 to an oscillatable plate 58, carrying a pin 59 movable into the path of a dog 60 attached to the rim 13. The lever 56 also has a crank 61, which is connected by a link 62, through a lost motion slot 63, to a pin 64 located in the end of control lever 20 65 of a pilot valve 66.

The lever 56 is mounted on the side of the knee, as shown in Figure 2, for movement by the operator in a counterclockwise direction, as viewed in Figure 8, to effect admission of compressed air 35 to the clamping cylinders 42, and simultaneously to position the pin 59 in the path of the dog 60. Due to the lost motion connection at 63 with the pilot valve control lever 65, the pilot valve will remain in its dash and dot position indicated by 40 the reference numeral 65'.

The broaching ram is assumed to be at the top of its stroke when the work is loaded and clamped. As the pistons 45 move upward to clamp the work, they release the pressure on opposite ends of an equalizer bar 67 pivotally connected at the center to a plunger 68, whereby the plunger moves upward along with the pistons 45 under the urge of a spring 69. As the plunger 68 moves upward, it rotates a bell crank 70 in a 45 counterclockwise direction. This crank has a third arm 71 in the end of which is mounted a spring pressed pin 72.

As the arm 71 moves counterclockwise, the pin engages a crank arm 73 integral with the lever 65 thereby rotating the lever 65 in a clockwise direction. This rotates the pilot valve into a position to connect the pressure port 74, which is supplied by a pump 75, to port 76, and simultaneously interconnects port 77 to a reservoir port 60 78. Ports 76 and 77 are connected by channels 79 and 80 to opposite ends of a reversing valve 81. Since the channel 79 is under pressure at this time, the plunger 82 of the reversing valve is shifted into its right hand position. This results in the pressure port 83 of the valve, which is supplied by a separate pump 84, being connected to port 85 whereby fluid will flow through the connected channel 86, and the central bore 87 in the piston rod 88, to the lower chamber 89 65 of ram cylinder 90.

The cylinder 90, as shown in Figure 8, is formed within the slide 13 whereby the cylinder becomes the moving member and the piston 91, contained within the cylinder, the fixed member. The upper end 92 of the cylinder is connected through a

second passage 93 in the piston rod to channel 94 that leads to port 95 of a double check valve 96. This valve has a first spring pressed plunger 97 which is opened by the returning fluid, so that it may continue through port 98 and channel 99 to port 100 of the reversing valve. This port is connected by an annular groove 101 to an exhaust port 102, which in turn is connected by channel 103 to the reservoir 104.

It will now be evident that the operator throws the lever 56 to effect clamping of the work, and after both work pieces have been properly clamped, a pilot valve is automatically operated to shift the reversing valve into a position to cause admission of fluid pressure to the ram operating cylinder in such a manner as to cause downward movement of the broaching ram.

After the broaching teeth pass by the work to complete the broaching operation, the ram continues its downward movement a sufficient amount to permit automatic work ejectors to engage the under side of the work pieces. One of these ejectors is shown in Figure 3 and comprises a hook shaped member 105 which is pivotally mounted on a pin 106 carried by the ram. 25 The ejector 105 is continuously urged in a clockwise direction by a spring pressed plunger 107, its movement being limited by an adjustable set screw 108 located on the side of the pin 106 opposite the plunger 107.

As the ram moves down, the beveled face 109 on the lower end of the ejector 105 engages the side of the work and is thereby rotated in a counterclockwise direction so as to move past the work piece. As the broaching ram approaches the end 35 of its stroke, the hook portion 110 snaps under the work piece in a position to raise the same upon upward movement of the ram.

As shown in Figure 5, the member 105 has two projecting lugs 111 and 112, and in order to insure that these will engage the under side of the work, the supporting ring is cut away to form two slots 113 and 114 into which the lugs 111 and 112 may enter. When the ram moves up, these lugs lift the work piece off of the mandrels and cause it to tip backward away from the rams so that it will fall into approximately the dash and dot outline position indicated by the reference numeral 115.

The downward movement of the ram is stopped by the dog 60 engaging the pin 59 thereby rotating the plate 58 in a counterclockwise direction, as viewed in Figure 8, and through the various linkage connections to valves 47 and 66, the air pressure is reversed in cylinders 42, and the pilot valve is operatively rotated counterclockwise to connect the pressure port 74 to port 77, and port 76 to exhaust port 78. This will cause fluid pressure to flow to the right hand end of the reversing valve shifting the plunger 82 into its left hand position thereby reversing the connections to the ram cylinder. At the same time, however, the fluid in channel 80 flows to the left end of a by-pass valve 116 shifting the plunger 117 to the right against the compression of a spring 118. 65 An annular groove 119 in this valve interconnects ports 120 and 121 whereby the fluid pressure existing in the space 122 of a relief valve 123 is by-passed to reservoir through channel 124, interconnected ports 120 and 121, and return line 125.

The pump 84 is continuously pumping fluid into the space 126 of relief valve 123 and this fluid is continuously acting on one end of the piston 127 which is slidably mounted in the valve 75

and normally held against movement by pressure in the space 122. But when the pressure in this space is by-passed to reservoir, the piston 127 shifts to the right, and the end of the piston rod 128 integral with the piston 127 uncovers port 129, whereby the pump 84 is by-passed to reservoir through channel 103 which has a branch connection to port 129. Thus, although the reversing valve plunger 82 is shifted to the left, the supply pump 84 is by-passed to reservoir and the ram will stop.

As the air pressure in cylinders 42 move the pistons 44 downward to unclamp the work, they engage opposite ends of the equalizer bar 67 moving plunger 68 downward against the compression of spring 69. This rotates the bell crank 70 in a clockwise direction.

The by-pass valve plunger 117 has a lost motion connection 130 with the end 131 of the bell crank 70, but at this movement the lost motion has been taken up due to the hydraulic shifting to the right. Therefore, when the bell crank 70 is rotated in a clockwise direction, it moves the plunger 117 to the left a sufficient amount to close the port 121. This will permit fluid in the space 126 in valve 123 to leak through a groove 132 in plunger 127 into the space 122 and since the end area of the piston 127 in space 122 is greater than the opposite end area of the piston 127 due to the fact that the piston rod 128 is larger in diameter than the piston rod 133, the piston 127 will gradually move to the left to close port 129.

When the port 129 has finally closed, fluid pressure will build up in channel 99 opening a second plunger 134 in valve 96, so that the same may continue to the upper end of the cylinder 90. The fluid in the lower end of the cylinder will return to reservoir through channel 96, interconnected ports 85 and 135 of the reversing valve, and return channel 103.

The double relief valve 96 insures that there will always be fluid in the upper end of cylinder 90 and thereby prevent the ram from accidentally dropping.

The ram moves up, ejecting the work in the manner just described until a dog 136 engages a trip lever 137. This rotates a valve 138 into a position to interconnect port 139 with port 140. The port 139 is connected by a channel 141 to channel 86 which at this time is connected to reservoir. The port 140 is connected by a channel 142 to port 143 of the relief valve 123 whereby the fluid in chamber 122 of the relief valve is by-passed to reservoir permitting the piston 132 to move toward the right and thereby open port 129 so that the delivery of pump 84 is by-passed to reservoir whereby upward movement of the ram stops.

The operator loads new work pieces in the work fixtures and the machine is ready to repeat the cycle. In doing this the dog 136 will start down with the ram and rotate the valve 138 into engagement with the second trip lever 144 thereby closing the by-pass connection to reservoir from port 143 of the relief valve 123. This by-pass connection is previously closed at another point, however, in order that the relief valve might close so that the ram could start its downward movement. This was accomplished when the reversing valve plunger 82 shifted to the right because up until this time, the port 85 was connected to reservoir. When the reverse valve plunger 82 shifted to the right, the circuit was closed so that the necessary pressure could build

up in the space 122 and thereby shift the piston 127 to the left.

For emergency stopping, the channel 124 is provided with a branch connection 145 to reservoir in which is a valve 146 which is adapted to be rotated by either the manually operable handle 147, or the foot pedal 148 which is connected to the valve lever 149 by a link 150. When this valve is rotated in a clockwise direction, the branch 145 is connected to reservoir thus relieving the pressure in the chamber 122 of valve 123 causing the port 129 to open.

There has thus been provided an improved broaching machine which has an improved control circuit for simultaneously broaching a plurality of work pieces together with automatic ejecting means, and sequential interlocks to insure that each successive step in the cycle has been completed before the next motion is undertaken.

What is claimed is:

1. In a broaching machine having a work support and a broaching ram movable relative to said support, the combination of a work receiving mandrel mounted on said work support with its axis parallel to the direction of movement of said ram, means for clamping the work, means for unclamping the work during movement of the ram in one direction, and means carried by the ram for lifting the work piece off the mandrel during ram movement in an opposite direction.

2. In a broaching machine having a work support and a power operable broaching ram movable relative to said support, manually operable means for clamping a work piece to said support and causing a feeding movement of said ram, automatically operable means for stopping the ram and unclamping the work at the end of the broaching stroke, and means carried by the ram for automatically ejecting a work piece during its return stroke.

3. A broaching machine having a work support, a plurality of work receiving mandrels mounted on said support, a broaching ram, a plurality of broaching tools carried by the ram, means to move the ram to effect simultaneous broaching of the several work pieces, means to return the ram, and means carried by the ram and effective during its return stroke for removing the several work pieces from the respective mandrels.

4. In a broaching machine having a work support, the combination of a broaching ram movable in one direction past said support for effecting a broaching operation, and work removing means carried by the end of the broaching ram for engaging and removing a work piece from the support during movement of said ram in an opposite direction.

5. In a broaching machine having a work support and a broaching ram movable relative to said support, the combination of means for clamping a plurality of work pieces on the work support for simultaneous broaching, power operable means for effecting a broaching stroke of said ram, a plurality of broaching tools carried thereby for engagement with the respective work pieces, trip operable means for stopping the downward movement of the ram and causing automatic unclamping of the work, and means responsive to said unclamping means for initiating return movement of the ram.

6. In a machine tool having a work support, a broaching ram, a plurality of parallel

- arranged broaching tools on said ram, the combination of a plurality of work receivers on the work support, individual power operated clamping means associated with each receiver, power operable means for reciprocating said ram, including a reversing mechanism, trip operable means for releasing said power operated work clamps at the end of the broaching stroke, and interlocking means for preventing said reversing mechanism from becoming effective until all of said power operated clamps have been released.
7. In a broaching machine having a work support and a broaching ram, the combination of fluid operable means for reciprocating said ram, including a supply channel, a pump, a pressure closed relief valve connecting said pump to said channel, and trip operable means for releasing the pressure in said valve to stop the movement of the ram.
- 20 8. In a broaching machine having a work support and a broaching ram, the combination of fluid operable means for reciprocating said ram, including a supply channel connected to said ram, a pump, a pressure closed relief valve for maintaining the pump operatively connected to said channel, trip operable means for by-passing the holding pressure in said relief valve for stopping the ram at the end of its stroke, and additional means for by-passing the holding pressure at any time for emergency stopping, including a manually operable lever and a pedal operable lever.
9. In a broaching machine having a work support and a broaching ram, the combination of fluid operable means for shifting said ram, including a reversing valve, a relief valve connecting said pump to the reversing valve, means to establish a holding pressure in said relief valve for maintaining the same closed, a by-pass valve for said holding pressure, fluid operable means for shifting said reversing valve, and said by-pass valve, whereby the reversing valve will be positioned to change the movement of the ram, but the pump will be by-passed to reservoir, a work clamping means carried by the work support, and means operable by said work clamping means upon movement to a work releasing position to close said by-pass valve and thereby initiate movement of the ram.
- 50 10. In a machine tool having a work support and a broaching ram, the combination of fluid operable means for reciprocating said ram, including a pilot valve for determining the direction of ram movement, a work clamping member carried by the work support having a first position for clamping the work, and a second position for unclamping the work, and means responsive to the positioning of said member reacting on the pilot valve for determining the position of said pilot valve.
11. A control mechanism for a broaching machine or the like embodying a plurality of work clamping devices and a ram member mounted for translation with respect to said devices, said mechanism including multiple independently shiftable work clamping members, a power transmitting member variably positionable by different movements of the work clamping members, means providing a pilot control circuit including a shiftable valve, operative connections between the clamp controlled member and said valve, a main actuating circuit including an effective pressure determining valve, an operative connection between the pilot valve and said main circuit control valve whereby the pilot circuit

will differently react on the valve dependent on the position of the pilot valve, and a lost motion connection between the clamp controlled member and said valve whereby said valve may be actuated with or relative to the controlled member in different clamp determined positions thereof. 5

12. A control mechanism for a broaching machine or the like embodying a plurality of work clamping devices and a ram member mounted for translation with respect to said devices, said mechanism including multiple independently shiftable work clamping members, a power transmitting member variably positionable by different movements of the work clamping members, means providing a pilot control circuit including a shiftable valve, operative connections between the clamp controlled member and said valve, a main actuating circuit including an effective pressure determining valve, an operative connection between the pilot valve and said main circuit control valve whereby the pilot circuit will differently react on the valve dependent on the position of the pilot valve, a lost motion connection between the clamp controlled member and said valve whereby said valve may be actuated with or relative to the controlled member in different clamp determined positions thereof, valve means for determining the operative position of the work clamps and linkage interconnecting said valve means and the pilot valve for effecting simultaneous actuation thereof. 20

13. A control mechanism for a broaching machine or the like embodying a plurality of work clamping devices and a ram member mounted for translation with respect to said devices, said mechanism including multiple independently shiftable work clamping members, a power transmitting member variably positionable by different movements of the work clamping members, means providing a pilot control circuit including a shiftable valve, operative connections between the clamp controlled member and said valve, a main actuating circuit including an effective pressure determining valve, an operative connection between the pilot valve and said main circuit control valve whereby the pilot circuit will differently react on the valve dependent on the position of the pilot valve, a lost motion connection between the clamp controlled member and said valve whereby said valve may be actuated with or relative to the controlled member in different clamp determined positions thereof, valve means for determining the operative position of the work clamps and linkage interconnecting said valve means and the pilot valve for effecting simultaneous actuation thereof. 35

14. A control mechanism for a broaching machine or the like embodying a plurality of work clamping devices and a ram member mounted for translation with respect to said devices, said mechanism including multiple independently shiftable work clamping members, a power transmitting member variably positionable by different movements of the work clamping members, means providing a pilot control circuit including a shiftable valve, operative connections between the clamp controlled member and said valve, a main actuating circuit including an effective pressure determining valve, an operative connection between the pilot valve and said main circuit control valve whereby the pilot circuit will 40

differently react on the valve dependent on the position of the pilot valve, a lost motion connection between the clamp controlled member and said valve whereby said valve may be actuated with or relative to the controlled member in different clamp determined positions thereof, valve means for determining the operative position of the work clamps and linkage interconnecting said valve means and the pilot valve for effecting simultaneous actuation thereof, a yielding connection intervening the pilot valve and the clamp actuated member whereby the valve may be positioned by or with respect to said member, and interengaging means carried respectively by the ram and the work clamp valve for effecting definite positioning of the clamp and pilot valves in opposition to the reaction of said yielding connection.

15. A control mechanism for a broach or like machine tool which includes a hydraulically translatable ram member, means for supporting work in opposition to the ram member and releasable clamp mechanism for maintaining work pieces in position, said control mechanism including a first hydraulic actuating circuit for the ram having serially arranged power conditioning and reversing valves, a second hydraulic control circuit including a variably positionable pilot valve intervening the fluid pressure source and the reversing valve and reacting thereon for power positioning thereof, and valve means including elements actuatable by positioning of the pilot valve and elements independent of the positioning thereof, each reacting on the circuit condition determining valve to determine the flow reaction of the hydraulic power circuit on the translatable ram for a given positioning of the pilot and reversing valves.

16. A control mechanism for a broach or like machine tool which includes a hydraulically translatable ram member, means for supporting work in opposition to the ram member and releasable clamp mechanism for maintaining work pieces in position, said control mechanism including a first hydraulic actuating circuit for the ram having serially arranged power conditioning and reversing valves, a second hydraulic control circuit including a variably positionable pilot valve intervening the fluid pressure source and the reversing valve and reacting thereon for power positioning thereof, valve means including elements actuatable by positioning of the pilot valve and elements independent of the positioning thereof, each reacting on the circuit condition determining valve to determine the flow reaction of the hydraulic power circuit on the translatable ram for a given positioning of the pilot and reversing valves, an auxiliary control mechanism for determining the operative and inoperative position of the work clamps, and operative connections between the work clamp mechanism, the pilot valve and at least one of said condition determining elements for variably positioning said two last-named parts dependent on the opera-

tive position of the work clamp elements and their controls.

17. A control mechanism for a broach or like machine tool which includes a hydraulically translatable ram member, means for supporting work in opposition to the ram member and releasable clamp mechanism for maintaining work pieces in position, said control mechanism including a first hydraulic actuating circuit for the ram having serially arranged power conditioning and reversing valves, a second hydraulic control circuit including a variably positionable pilot valve intervening the fluid pressure source and the reversing valve and reacting thereon for power positioning thereof, valve means including elements actuatable by positioning of the pilot valve and elements independent of the positioning thereof, each reacting on the circuit condition determining valve to determine the flow reaction of the hydraulic power circuit on the translatable ram for a given positioning of the pilot and reversing valves, an auxiliary control mechanism for determining the operative and inoperative position of the work clamps, operative connections between the work clamp mechanism, the pilot valve and at least one of said condition determining elements for variably positioning said two last-named parts dependent on the operative position of the work clamp elements and their controls.

18. In a machine of the character described, the combination with a reciprocable broach carrying ram, of means for supporting work in opposition to the ram including clamping members and actuation controlling means therefor, a power circuit for determining reciprocation of the ram including a source of power, a circuit conditioning valve and a serially arranged reversing valve intervening the source of power and the ram, a valve element coupled with and reactable on the conditioning valve, a pilot circuit having branches coupled with the reversing valve and the element, a pilot valve for determining the effective couplings of the circuit with said last-named parts and operative connections including resilient actuators and lost motion devices intervening the clamp control mechanism, the pilot valve and said element, whereby shifting of the parts into clamped releasing position conditions the ram actuating circuit for reversal of the ram but interrupts actuation thereof and continued movement of the clamp control mechanisms reconditions the power circuit to effect subsequent reverse movement of the ram substantially as described.

WILLIAM D. AVERILL. 65
